Primary Examiner — Ryan Harvey(74) *Attorney, Agent, or Firm* — Brooks Kushman P.C.(57) **CLAIM**

The ornamental design for an elliptical cycle, as shown and described.

DESCRIPTION

FIG. 1 is a top perspective view of an elliptical cycle, embodying the new design;

FIG. 2 is a bottom perspective view thereof;

FIG. 3 is a rear elevation view thereof;

FIG. 4 is a front elevation view thereof;

FIG. 5 is a first side elevation view thereof;

FIG. 6 is a second side elevation view thereof;

FIG. 7 is a top plan view thereof; and,

FIG. 8 is bottom plan view thereof.

The broken lines shown are included for the purpose of illustrating the unclaimed portions of the article and form no part of the claim.

1 Claim, 8 Drawing Sheets(56)
